United States Patent Office

Des. 220,052
Patented Mar. 2, 1971

220,052

CANDLESTICK

Harold D. Stoner, 355 Adams St.,
Oakland, Calif. 94610

Filed Jan. 29, 1970, Ser. No. 21,129

Term of patent 14 years

Int. Cl. D26—05

U.S. Cl. D48—2

FIG_1

FIG_4

FIG. 2

FIG. 3

FIG. 1 is a top perspective view of the candlestick showing my new design;

FIG. 2 is a top plan view thereof on an enlarged scale;

FIG. 3 is a bottom plan view thereof on an enlarged scale;

FIG. 4 is a side elevational view thereof on an enlarged scale, the remaining three sides being identical to that shown.

The candles are shown in broken lines in FIGS. 1 and 2 for illustrative purposes only.

I claim:

The ornamental design for a candlestick, as shown and described.
